OIL BURNER FUEL CONTROL

William O. Behrens, Harvey, Ill.

Application March 6, 1941, Serial No. 381,949

2 Claims. (Cl. 158—36.3)

The invention relates to oil burners and more particularly to means for controlling the flow of fuel oil to the nozzle of an oil burner of the variable capacity type.

It is a general object of the invention to provide a novel fuel oil control circuit which is characterized by its extreme simplicity, yet which is capable of exceptional performance in the delivery of variable, but precise quantities of fuel oil to the nozzle of a burner over wide ranges of capacity, oil viscosity and temperature conditions.

It is another object of the invention to provide a new and improved oil flow circuit which eliminates carbon formation due to after flow of oil following a shut down of the burner.

It is a further object of the invention to provide a novel oil flow circuit for a burner which assures proper combustion air supply during starting and provides smooth ignition.

It is a still further object of the invention to provide new and improved apparatus of this type capable of supplying high viscosity fuel oils to a burner over a wide range of capacities and temperatures and at the same time maintaining a constant oil-air ratio adjustment.

Other objects and advantages will become apparent as the following description proceeds taken in connection with the accompanying drawing in which:

Figure 1 is a perspective view of an oil burner having associated therewith an oil flow control circuit incorporating the features of the present invention.

Fig. 2 is a diagrammatic view of the oil flow control circuit shown in Fig. 1.

While the invention is susceptible of various modifications and alternative constructions, I have shown in the drawing and will herein describe in detail, the preferred embodiment, but it is to be understood that I do not thereby intend to limit the invention to the specific form disclosed, but intend to cover all modifications and alternative constructions falling within the spirit and scope of the invention as expressed in the appended claims.

Referring more particularly to Fig. 1 of the drawing, I have illustrated generally therein merely for purposes of disclosure one form of fuel oil burner adapted for use in connection with the fuel oil flow control circuit of the present invention. In the present instance the perspective view (Fig. 1), taken from the rear and at one side of the apparatus, illustrates a burner housing 10 which encloses the burner mechanism.

This mechanism, which constitutes no part of the present invention, may be of the general type illustrated and described in my Patent No. 2,202,822, its primary function being to discharge a stream of air and finely atomized fuel oil into a furnace. To this end, it may include an electric motor 11 (Fig. 2) which drives a blower (not shown) for delivering forced draft combustion air to the region of a fuel oil atomizer 12, which may also be suitably actuated by the burner motor. An air damper 13 is interposed in the path of the air flow to the region of the atomizer and is adjustable by means indicated at 14 to regulate the quantity of combustion air supplied in accordance with the kind and amount of fuel oil delivered. A fuel oil supply line 15 enters through the rear wall of the burner housing and may be suitably connected to deliver variable quantities of oil to the atomizer located at the front of the burner.

In an oil burner of this type, it is essential that the ratio of fuel oil and combustion air supplied to the combustion chamber be regulated accurately for efficient combustion over various capacity ranges. In other words, when the amount of fuel oil delivered to the burner is increased, a proportionate increase in the supply of combustion air must be provided. Accordingly, provision is ordinarily made for conjoint control of fuel and air so that a substantially constant ratio may be maintained in increasing or decreasing the rate of oil delivery to the burner. In burning oils of low viscosity under uniform temperature conditions, not giving rise to variations in viscosity, the problem of maintaining a substantially constant fuel-air ratio is relatively simple. Variable quantities may be supplied through ordinary metering valves effecting a mere throttling operation which may be made substantially proportionate to a similar throttling of the combustion air. Considerable difficulty is encountered, however, in attempting to meter or throttle oils, particularly those of heavy viscosity, under varying temperature conditions and also in attempting to meter oils of different specific viscosities in the same installation and over varying capacity ranges.

One rather costly and complicated solution which has been suggested heretofore for metering fuel oil over varying temperature ranges is the provision of a so-called viscosity metering valve. A valve of this type is adjustable automatically for changes in viscosity, the adjustment being responsive to changes in the oil pressure. In other words, when the temperature of the oil

is raised the pressure is decreased due to a lower viscosity, and when the oil is cold, the viscosity being higher, the pressure is correspondingly higher. In such installations the valve orifice is automatically enlarged or diminished as the oil pressure changes in response to changes in temperature. Viscosity metering valves have not been found wholly satisfactory, however, for the reason that the automatic adjustment for viscosity changes, responsive to oil pressure, cannot be made correctly proportional to attain a constant oil-air ratio over different capacity ranges. An adjustment which is correct in one range of burner capacity is not correct for another range. In other words, assuming that the viscosity metering valve is so constructed as to provide a proper adjustment for changes in viscosity when the burner is operating at full capacity, the valve will be incapable of compensating for viscosity changes in lower ranges of capacity or when the valve has been throttled. Similarly, in burning fuel oils of various specific viscosities in the same installation, an adjustment which will correctly compensate for variations due to temperature changes for one oil will not correctly compensate for another oil of a different specific viscosity.

The importance of maintaining a substantially constant fuel air ratio is emphasized in industrial burners where large quantities of high viscosity oils are utilized as fuel over long periods of time. Under such circumstances, lazy or smoky fires in the combustion chambers result in carbon formation, reduced burner capacities and inefficient fuel consumption. I have accordingly provided an extremely simple apparatus for delivering variable, yet precise quantities of fuel oil to the atomizer of an oil burner over wide ranges of capacity, oil viscosity and temperature conditions. The system utilizes a positively operated adjustable metering pump in conjunction with means such as a circulating pump or gravity feed for assuring, at all times and under all conditions of temperature and oil viscosity, an ample and readily available supply of oil for the metering pump.

In the present instance, the apparatus comprises a circulating pump 16 drivingly connected with the burner motor 11 and adapted to draw oil from a suitable source of supply through a conduit line 17 herein illustrated as passing through a hinge 18 of the burner front plate. The circulating pump delivers oil under a substantially constant pressure to an adjustable metering pump 19 through suitable oil lines 20 and 21. On the delivery side of the circulating pump a simple by-pass or bleeder 22 is provided for the return passage of excess fuel oil to the source through a conduit oil line 23 which may be arranged to pass through the lower hinge of the burner front plate. The metering pump may be of any suitable type capable of delivering positively a specific volume of fuel oil to the oil line 15 regardless of its viscosity, provided an ample supply is readily available. Preferably, the pump is of the rotary, radially slideable vane type where provision is made for varying the eccentricity of the pumping chamber relative to the rotor provided for carrying the radially slideable vanes. The details of construction of a metering pump suitable for the purpose, but constituting no part of the present invention, are disclosed in my Patent No. 2,302,411, issued November 17, 1942. As illustrated in Fig. 1 of the drawing, an adjusting shaft 24 extends axially from the metering pump housing and is adapted for conjoint

actuation with the air damper adjusting means 14 through the agency of a rod 25. The metering pump may be suitably driven from the burner drive shaft 26 through such means as worm gearing 27.

It will be apparent that the circulating pump 16 which is driven from the burner motor will provide a constant and ample supply of fuel oil for the metering pump 19 under all operating conditions, regardless of variations in oil viscosity due to temperature changes and irrespective of the type or grade of oil burned. With this ample and readily available supply the metering pump 19, also driven from the burner motor, will be capable of delivering exactly the same quantity of oil for any given setting irrespective of variations in oil viscosity and temperature. The metering pump will be subject to no variable and fluctuating back pressures to impair the accuracy of its positive volume delivery. Having thus provided means for delivering a precise quantity of oil for every throttle or capacity position regardless of viscosity changes, it is a simple matter to adjust the air-oil ratio to a constant value for the entire capacity range of the burner. Another advantage inherent in this series arrangement of a circulating and a metering pump is the elimination of troublesome and costly relief valves which must be utilized in connection with viscosity metering valves. Since metering valves of this type require pressure in order to meter the oil, a simple T by-pass for the relief of excess oil is not operative. Similarly the arrangement has marked advantages over prior art systems utilizing needle valves which have a tendency to gum up and clog in continuous service.

Means for positively stopping the oil flow when the burner is shut down, in the present instance, comprises a solenoid operated shut-off valve 28 located in the oil line 20-21 between the metering pump and the circulating pump and ahead of the by-pass 22. To actuate the valve, its solenoid is connected in the burner motor circuit 29, 30 by conductors 31, 32 for concurrent energization with the burner motor. The valve 28 is located on the suction side of the metering pump and, since it is wired in the motor circuit, it will close instantly when the burner is shut down to interrupt the flow of oil between the circulating pump and the metering pump. The burner motor 11, and accordingly the metering pump 19, has a period of overrun of approximately 30 seconds after the circuit is opened and, since the pump intake is closed, substantially all fuel oil is exhausted from the pump during this overrun. The small amount of oil remaining in the discharge pipe or line 15 drains into the hot burner and is consumed before the burner cools. After-flow or so-called "after-dribble" of oil from the nozzle, following the cooling down of the burner, is thus eliminated and carbon formation around the nozzle and atomizer is materially reduced.

An inherent characteristic of the present arrangement is a time delay of approximately 15 seconds after starting the burner, before the oil reaches the atomizer, since the oil line from the pump to the burner nozzle as well as the pump chamber must be refilled. Expensive relays with built-in time delay mechanisms which have been frequently provided to accomplish this end are thereby eliminated and fully atomized oil with a proper quantity of combustion air is supplied to effect a smooth ignition without "puffs" or "flash-back." Furthermore in burning extremely heavy or high viscosity oils where preheating of the oil

is required, an electric heater 33 may be positioned to surround the oil conduit 20 adjacent the solenoid valve 25. Since the oil line 15 to the atomizer and the pump are substantially empty when the burner is idle, the oil supplied to the nozzle first in starting will be preheated to further facilitate smooth ignition and eliminate difficulties in starting normally encountered after the burner has been idle for a period of time. It will be seen also that the valve 28 is constructed so that the suction of the metering pump will facilitate its closing. During the overrun period of the metering pump after the control circuit is broken, the suction created in the line between the solenoid valve and the metering pump is especially valuable with heavy fuel oils to insure a rapid and tight closure of the valve. Thus, the use of a lighter weight and less powerful solenoid is permitted.

I claim as my invention:

1. The combination with an oil burner of the type having power driven combustion air supply means, of an electric motor arranged to drive the air supply means, an operating circuit for said motor, a metering pump driven by said motor operative to deliver fuel oil to the burner at a predetermined rate, means for delivering a readily available supply of fuel oil to the intake of said metering pump, a shut-off valve interposed in the intake of said metering pump, a solenoid connected in the motor circuit and operative to open said valve when the motor circuit is closed and to close said valve when the motor circuit is open, said motor adapted to coast for an interval following the opening of its circuit and the closure

5 of said shut-off valve whereby substantially all fuel oil is exhausted from said pump, the filling of said pump upon the starting of the motor acting to interpose a delay in the delivery of fuel oil to the burner whereby to insure an adequate air supply for starting the burner.

2. The combination with an oil burner of the type having an atomizer located in close proximity to the combustion zone of the burner, means 10 for supplying combustion air to said combustion zone, an electric motor arranged to drive said air supply means, a metering pump driven by said motor and adapted to deliver fuel oil directly to said atomizer at a predetermined rate, a circulating pump driven by said motor and adapted to deliver fuel oil to the intake of said metering pump, a shut-off valve interposed between said circulating and metering pumps, a solenoid 15 adapted when energized to open said valve and when deenergized to permit the valve to close, means connecting said solenoid in circuit with said motor whereby said solenoid is energized when the motor circuit is closed and deenergized when the motor circuit is opened, said motor adapted to coast for an interval following the 20 opening of its circuit whereby said metering pump is enabled to assist in closing said valve and to completely empty its chambers of fuel oil so as to prevent any flow of oil while the burner is shut down, the filling of the chambers of said pump upon the subsequent starting of said motor serving to interpose a delay in the delivery of fuel oil to the atomizer and thereby insure an adequate air supply for starting the burner.
